INVENTOR

Frank M. Slough

UNITED STATES PATENT OFFICE.

FRANK M. SLOUGH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

TELEPHONE SYSTEM.

1,351,800.

Specification of Letters Patent. Patented Sept. 7, 1920.

Application filed March 31, 1917. Serial No. 158,863.

To all whom it may concern:

Be it known that I, FRANK M. SLOUGH, residing at Rochester, in the county of Monroe and State of New York, a citizen 5 of the United States, have invented certain new and useful Improvements in Telephone Systems, of which the following is a full, clear, concise, and exact description, reference being had to accompanying drawings, 10 forming a part of this specification.

The invention relates to that class of telephone systems, wherein means are provided to connect any one of a plurality of telephone lines to an idle operator's telephone 15 circuit, and wherein it is desired to complete the connection by connecting switches under the control of the central station operator.

An object of my invention is to provide 20 means whereby the connection between the calling line and the operator's circuit is effectively controlled partly in an automatic manner, and partly by manually operated apparatus whereby the subscriber can receive 25 the maximum of service from the attendant operator; and can be connected to a called-for line without undue loss of time.

Another object is to provide means to cut 30 down the holding time of trunk circuits and the operator's call circuit involved in a connection to the minimum without disassociating such connection for a predetermined length of time, after said subscriber has given the disconnect signal.

Another object is to provide an operator's 35 call circuit to operate in connection with a call distributing system of a particular type as will be more particularly set forth in the description of the system following and in 40 which reference will be made to the drawings which are a part of this specification.

An additional object of this invention is to accomplish the final act of making connection by means of any one of a number 45 of idle connector switches associated with a group of incoming call circuits, whereby any incoming connection residing in any one of the incoming call circuits can be extended to any selected idle connector switch.

50 A further object of this invention is to provide means whereby the operator's telephone set is connected to the incoming call circuit, and by means of the same connected to the telephone of the calling line prior to

the selecting of a connector switch by the 55 operator, whereby the operator can receive instructions from the calling subscriber.

In the figures I show an embodiment of my invention operating in connection with a call distributing telephone system in 60 which a telephone subscriber upon initiating a call will be automatically connected to a particular call circuit of the system, such connection being preferably made to an idle call circuit of an idle operator's 65 position.

In the embodiment illustrated I also arrange the call circuits of an operator's position in association with a plurality of connecting plug circuits, the arrangement being such that any of said plug circuits may be used to complete the connection of any incoming call circuit to a desired telephone line terminating in a jack adjacent to the 70 plug circuits.

It is a common practice in connection with call distributing systems to associate with each connecting circuit a set of party line ringing keys, in systems wherein party line selective signaling is contemplated, so 80 that after depressing a particular button to cause the selective signaling of the desired subscriber on the party line, the condition of such button, it remaining in some abnormal position, indicated to the operator 85 thereafter during the connection period which party had been called. This requires the use of numerous sets, usually of interlocked switching keys on an operator's position which has been found undesirable, expensive and unnecessary, since at any one 90 time an operator can only operate one of said keys at a time.

In the accompanying drawings in Figure 1, I show the originating end of two telephone lines and the means whereby the lines are successively connected to non-busy central office trunks from different groups of substantially the same character.

Fig. 2 shows the apparatus subsequently 100 involved whereby the incoming call is connected to a non-busy operator's incoming call circuit, the details of which are shown in this figure.

Fig. 3 shows the means whereby the operator's circuit is extended to a desired connector switch, by means of which the connection is extended to the called-for line. 105

Fig. 1, shows two telephone lines L_1 and L_2 leading from jacks J_1 and J_2 at the main exchange, to substations S_1 , S_2 , S_3 and S_4 on line L_1 , and substations S_5 , S_6 , S_7 and S_8 on line L_2 . These lines are party lines there being a plurality of stations thereon, and in this embodiment, the bells are what are known as harmonic bells, each being capable of operation only by a particular frequency of current pulsations.

At the main exchange and associated with the line jacks of the lines, are line and cut-off relays—alike, for each of the lines, the line relays being indicated at 1, and cut-off relays at c .

The two limbs of the line connected to the jacks are extended as well to connection switches, which are shown in this embodiment as relay contacts, by conductors 1 and 2, leading to the contacts 3 and 4 of a plurality of connecting relays, these relays for line L_1 being indicated at R_1 , R_2 and R_3 . I have illustrated in Fig. 1, two lines equipped alike, although it is obvious that a greater number would be connected to the system. I have also shown with each of the lines three relays as above mentioned, each of which is capable of connecting conductors from its line circuit to conductors of an intersecting trunk circuit, there being arranged in the Fig. 1, three such intersecting trunk circuits, the same being designated at A, B and C.

I will describe in particular, only one set of connections whereby any incoming call is extended to a particular call circuit, although the apparatus is shown for completing other sets of connections.

At D and E, I show inter-trunk controlling relays which control inter-trunk connections.

At R_4 , R_5 and R_6 , I show connecting relays each adapted to connect one of the trunks, such as A, B or C to a trunk such as F. At the left of these relays I show other like relays, adaptable to connect the trunks A, B and C to a trunk G.

At D_1 and E_1 , I show a set of inter-trunk controlling relays similar to the above mentioned relays D and E.

The trunk F terminates at the bottom of Fig. 1, in conductors 5, 6, 7 and 8, and in Fig. 2, I show these conductors 5, 6, 7 and 8 leading to an incoming call circuit, the same being shown in the upper right side of the drawing. This incoming call circuit consists of a plurality of relays, suitable circuit connections for connecting them, together with circuit conductors leading therefrom to the common controlling, indicating and supervising apparatus shown at the bottom of the figure.

Also means are shown to isolate a call circuit from the path of incoming calls when such a call circuit is once taken for use.

Circuit conductors 9, 10, 11 and 12 lead from this incoming call circuit to connecting relays R_7 and R_8 of Fig. 3, each of which is adapted to connect them to circuit conductors which lead to an associated plug connecting circuit—two of which are shown in Fig. 3, at X and at Y.

The act of the operator in inserting the plug of the particular chosen plug circuit into the jack of the called-for line will determine which of the connecting relays will be operated. Two telephone lines L_3 and L_4 are shown in this figure, each of which is shown as containing four party line telephones such as indicated on line L_1 and L_2 as previously briefly described; the central office apparatus of these line circuits is incompletely shown—that portion only being shown as is used for outgoing connections; that is, connections from the central office to the called-for party's telephone. The circuit leading to the connecting relays for incoming calls is not shown, as these are not used for out-going calls.

The plugs of the plug connecting circuits are adapted to be inserted in the jacks of either of the lines and there being a plurality of plug circuits adaptable for use in connection with any incoming call, the operator is enabled to prepare for a connection to a line either to the right or to the left of her, using for the purpose the plug circuit, the plug of which she holds in the hand nearest the jack of the called-for line; thus a shifting of the plug from one hand to the other is eliminated and time is saved.

The line L_3 contains four telephones and as shown has signal bells at each telephone, the bells being designated B_1 , B_2 , B_3 and B_4 . These bells are tuned to respond to current pulsations of its own particular frequency. The current pulsations are produced in the embodiment illustrated in the drawing of Fig. 2 by the generators G_1 , G_2 , G_3 and G_4 , respectively.

I provide as shown in Fig. 2, a plurality of ringing keys K_1 , K_2 and K_3 for setting up circuit connections whereby when the connection is completed by the insertion of the plug of the plug circuit into the jack of the called-for line, current pulsations will flow from one of the sources of current G_1 , G_2 or G_3 , corresponding to the particular key. In such a case current will flow from the generator G_4 , the circuit connections of the call circuit being such that this generator is connected to the called-for line if prior to the completion of the connection no key has been depressed.

A key K_4 , is provided to break down the set up ringing connections if the operator has made a mistake and depressed the wrong key, or for any other reason desires to correct the depression of a certain key. The four keys K_1 , K_2 , K_3 and K_4 , are all com-

mon to a group of call circuits. Two call circuits are illustrated in Fig. 2, and a description of the one will suffice for a description of both, for they are alike.

Referring now to Fig. 2, we will assume that one of the subscribers on line L_1 , makes a call, for instance, the subscriber S_1 on the line L_1 , thereby causing the line relay l to attract its armature and close a circuit from battery through its winding w , thence through the right hand winding of the relay R_1 , the conductor 13, the left hand winding of the inter-trunk controlling relay E , and the normally made contact of the associated relay D to ground at G . This circuit being closed battery current will flow causing the operation of relays R_1 and E . The relay E being operated another circuit will be closed starting at ground G_1 through a pair of make contacts of the relay E , the right hand winding of the relay E , the conductor 14, the right hand winding of the relay R_6 , the conductor 15, the left hand winding of the relay E_1 , normally made contacts of the relay D_1 , thence over the conductor 16 to battery. This circuit being completed battery will flow over the same operating the relays R_6 and E_1 , and retaining in its operated position the relay E . The relay E_1 being operated will in turn complete a circuit from ground at G_2 through make contacts of the relay E_1 and the winding thereof, the conductor 8 of Fig. 2, the winding of the relay N , the conductor 17, normally made contacts of the relay O , the conductor 18, the winding of the relay P , through battery and again to ground. This circuit being closed the relays N and P will be operated, and the relay E_1 will be for the time being retained in operation.

I have now described how certain relays will be operated upon the operation of a subscriber's switch-hook on the line L_1 . The following connecting relays have been shown as being operated, R_1 , R_6 and N ; the following controlling relays have been operated, E , E_1 and the relay P . The connecting relays R_1 , R_6 and N being operated the circuit of the line wires 1 and 2 shown in Fig. 1, will be completed through contacts 3 and 4 of the relay R_1 , contacts 19 and 20 of the relay R_6 , and contacts 21 and 22 of the relay N , so that line wires are thereby extended to the battery feed windings b and d of the relay Q . This relay Q will thus feed battery to the subscriber's telephone in parallel with the source of current normally in the line circuit of the subscriber's telephone, and will be operated attracting its armatures and switching circuits as will be later described.

When the connecting relays R_1 , R_6 and N were operated an additional circuit was completed containing a winding of each of these relays, and including the winding of the

cut-off relay c of the line as follows: from ground through the winding of the cut-off relay c of the line L_1 , the conductor 23, make contacts 24 of the relay R_1 , the winding of the relay R_1 , the conductor 136, the winding of the controlling relay D , conductor 26, make contacts 27 of the relay R_6 , the winding of the relay R_6 , conductor 28, the winding of the controlling relay D_1 , the conductor 7 leading to conductor 7 of Fig. 2, the second winding of the relay N , make contacts 29 of the relay N , circuit and conductor 30, the make contacts 31 of the relay Q , and to the negative pole of battery connected thereto.

This circuit being completed battery current will flow over the same, thus retaining in operation the connecting relays R_1 , R_6 and N , and also operating the controlling relays D and D_1 , and the cut-off relay c of the line circuit. The relays D and D_1 , being operated will in like manner open one winding and short circuit the second winding of their associated relays E and E_1 , so that these relays will be restored to normal. Furthermore, the relays D and D_1 , will attract their armatures 32 and 33 opening the circuits of the operating windings of the relays R_1 and R_6 and associated connecting relays, so that another line making a call will not be connected to the same trunk circuits taken for use as described, namely, the trunk circuits C and F .

The relay D upon attracting its armature 32 will close contacts 34, completing a circuit to ground through the normal contacts 35 of the relay D of trunk circuit B , so that this trunk circuit will be the next to be taken for use by a calling line in the same group as the line L_1 . In like manner the armature 33 of the relay D_1 will close its contact 36, thus completing a circuit to battery over the conductor 16, the conductor 37, and the normal contacts of the relay D_1 of the trunk circuit G , so that this trunk will be the next of its order to be taken for use by intersecting trunks of the same grouping as the trunk C upon the initiating of a call to be connected to a trunk of such grouping.

The cut-off relay c being operated will de-energize the line relay l by opening one winding thereof and short circuiting its other winding, and will likewise open the connection to ground at contacts 38, so that the line conductors will be clear of any connections to battery or ground, except through the windings b and d of the relay Q of Fig. 2.

Referring now to Fig. 2, it will be seen that the circuit of the operator's relay R has been held open up to this time at the contacts 39 of the relay P ; this relay is now restored to normal by the opening of its circuit at the contacts 40 of the relay E , when this relay was restored to normal, and

the contacts 39 are again closed, thus closing the circuit of the operator's relay R after an appreciable length of time subsequent to the connections being made, so that the operator's receiver when connected to the circuit through contacts of the relay R which will now be operated will not produce a noticeable or objectionable "click."

The operator's receiver is connected to the 10 circuit by means of the circuit conductors 41 and 42, 43 and 44 through contacts 45 and 46 of the relay R now operated, circuit conductors 47 and 48, and the conductors 5 and 6 which are connected to the subscriber's line conductors as before described. Thus the operator can at this time request 15 the desired number of the subscriber, and receive a reply specifying the particular telephone station with which connection is 20 desired.

Assuming that connection is desired with a party line telephone station, such as the station Z_1 on the line L_3 , the operator will proceed to set up the ringing connections in 25 the call circuit at the right of Fig. 2 being described, by depressing the key K_1 , thus closing two like circuits from ground through the contacts of the key K_1 , the conductors 49 and 50, the make contacts 51 and 52 of the relay R, the conductors 250 and 253, the windings of the relays S and T to negative pole of battery, thus operating the relays T and S, which relays will attract their armatures and switch circuits in 30 a manner to be described.

The depressal of the key K_1 need only be momentarily made as a holding circuit is provided for the relays S and T as follows:—from ground to the normally made 40 contacts of the key K_4 , the conductor 53, now made contacts 149 of the relay R, the conductor 55, the now made contacts 56 of the relay N, the conductor 57 and the like armatures 58 and 59 of the relays S and T, and therefrom through the make contacts 45 of said armatures, through the windings of the relays S and T to the negative pole of battery. Thus the relays S and T will remain energized even after the key causing 50 their operation has been released. The relays S and T now being operated, the armatures 60 and 61 of the relay S and the armature 62 of the relay T will be attracted closing make contacts 55 and breaking their normal contacts, so that there will be connected to the conductor 63 leading to the ringing contacts 64 of the ringing relay U, the ringing generator G_1 , current from said generator flowing 60 intermittently through the interrupter I, and over the conductor 65 leading to the call circuits, over a circuit as follows:—the conductor 65, the resistance lamp 66, the conductor 67, the make contact 68 of the

relay S, the make contact 69 of the relay 65 T, the armature 62 of the relay T, conductor 63, the winding of the trip relay V, the conductor 67 to the make contact 64 of the ringing relay U which contacts are at present open, but when closed the contact 64 70 will complete the circuit of the generator G_1 just described to the conductor 10 leading to the called subscriber's line as will be later described. The circuit of the ringing generator G_1 is therefore in effect set for use, 75 but at the contacts of the relay U the ringing circuit remains open for the present.

The operator now, having depressed the key K_1 may desire thereafter to know which key had been momentarily depressed and as 80 a result, which ringing generator circuit had been set for use in the call circuit under observation. I provide means for doing this requiring the operation of the listening key K_5 . When this key is depressed a circuit is 85 closed through one of the party line indicating lamps, 70, 71, 72 or 73, which lamps are common to the operator's position, the particular lamp lighted depending upon which one of the ringing keys, K_1 , K_2 or K_3 , 90 had been depressed. Assuming that the key K_1 had been depressed as has just been described just operating the relays T and S, the lamp 73 would be lighted over a circuit as follows: from the negative pole of battery, the winding of the relay W, the lamp 73, the conductor 74, the make contact 75 of the relay S, the conductor 76, the make contact 77 of the relay T, the conductor 78, the conductor 79, the now made contacts 80 of 100 the key K_5 to ground at 81. It will be seen that if one only of the relays S and T were operated by the choice of the particular key which would operate only one of these relays, that one of two lamps would be lighted, either the lamp 72 or the lamp 71; that if both of the relays were operated as in the case just described the lamp 73 would be lighted, and that if neither of the relays were operated as when none of the party 110 line keys are depressed and the circuit is thereby automatically set for first party or individual line ringing, then the lamp 70 would be lighted, the particular lamp lighted depending upon the circuit of the contacts of the two relays S and T. Thus the key K_1 controls the connection of the ringing generator G_1 to the ringing relay contacts, and when the listening key K_5 is depressed after the momentary depressal of 115 the key K_1 , the lamp 73 will be lighted to indicate which ringing key, and therefore, which generator had been previously set. In like manner the lamp 72 is the indicating lamp for the key K_2 , and the lamp 71 is the indicating lamp for the key K_3 , and the ringing generator G_2 , and the lamp 70 is the indicating 120 lamp for the key K_4 . The lamp 70 is the indicating lamp for the key K_4 , and the lamp 71 is the indicating lamp for the key K_3 , and the lamp 72 is the indicating lamp for the key K_2 , and the lamp 73 is the indicating lamp for the key K_1 .

lamp for the keyless or first party or individual line ringing by means of the generator G_4 .

The key K_4 is provided so that the energizing circuit for the relays T and S just described may be broken by the operator after inadvertently depressing the wrong ringing key, and the connection can then be set up in a correct manner.

To continue with the circuit operation narration—assuming that the key K_1 has been depressed causing circuit changes as previously described in detail, the next act of the operator in the system of my invention is to choose the particular plug connecting circuit to be used to extend a connection to the called line. In the system of the present embodiment of my invention herein shown, the operator is enabled to use with the incoming call circuits any of the group of plug circuits which is associated with the group of incoming call circuits under her care. We will assume therefore, that she chooses the plug circuit X to extend the connection to the line L_s , and the connection can now be extended by inserting the plug P_1 into the jack J_1 of line L_s .

The busy test will first be made in the usual manner by touching the tip of the plug P_1 to the thimble of the jack, and the presence or absence of a click in the operator's receiver will indicate the busy or non-busy condition of the line according to the well-known custom. The circuit will now be extended by the insertion of the plug P_1 in the jack J_1 , and this being done a circuit is closed including battery, the winding of the relay M and the cut-off relay c of the line L_s , thus operating both of these relays; the cut-off relay being operated performs the usual functions of such a cut-off relay which functions are well understood and need not be described.

The relay M upon being operated will attract its armatures, thus opening the busy test circuit, and closing other circuits to be described. One of these circuits closed is as follows:—from ground at 82, the make contacts 83 of the relay M , the conductor 84, the winding 85 of the relay R_7 , the conductor 11 of Fig. 3, the conductor 11 of Fig. 2, the winding 85 of the ringing relay U , the conductor 86, the make contacts 54 of the relay R , the normally made contact 88 of the relay O , and thence to negative pole of battery over conductor 89. This circuit being closed, battery will flow over the same through the windings of the relays U and R_7 , operating these relays; the relays U and R_7 being operated will attract their armatures causing circuits to be switched in a manner to be described.

The relay R_7 being operated will attract its armatures closing contacts 104, 105 and 117, thus extending the circuit conductors

9 and 10 to the plug contacts 109 and 110 through the now made contacts 108 of the relay M . The contact 117 being closed conditions a holding circuit which will be later described and which includes the winding 70 118 of the relay R .

The relay U being operated will attract its four armatures as follows: The second armature shown to the right of the relay U will be attracted forming a locking circuit 75 for the relay U , including its second winding 186 as follows:—from negative battery, the conductor 187, the winding of the relay 188, the circuit conductor 189, the now made contacts 90 of the relay U , the now 80 made contacts 91 of the relay U , the winding 186 of the relay U , the circuit conductor 92, the normally made contacts 93 of the relay 94, the circuit conductor 95, the normally made contacts 96 of the relay 97, the 85 circuit conductor 297, the normally made contacts 98 of the operator's key K_5 , and thence to the ground pole of battery by means of the circuit conductor 81. The relay U will thus be retained in operation for 90 the present, and the relay 188 will also be operated closing its contacts 99 for a purpose later to be described.

The relay U having attracted its armatures 100 and 101 and breaking the circuit 95 of the talking strands 102 and 103 leading back to the calling subscriber's talking conductors 5 and 6, through the contacts 21 and 22 of the relay N as has been described, connects generator current to the end of the 100 severed talking strands which extend by conductors 9 and 10 and by the now made contacts 104 and 105 to calling strands 106 and 107 of the plug circuit X . These line strands 106 and 107 now extend to the 105 limbs of the called-for line by means of the now made contacts 108 of the relay M , the tip and sleeve contacts 109 and 110 of the plug P_1 , the tip and sleeve coöperating contacts 111 and 112 of the jack J_1 of the 110 called-for line and the limbs 113 and 114 to the telephone substation on the line L_s , thus ringing the bell of the called-for substation which we have assumed in this description to be the subscriber having the 115 station Z_1 on the line L_s . The generator circuit leading to the now made contacts 64 of the relay U , has been previously described and includes the circuit of the trip relay V , and contacts of the relays T and S 120 which relays were set for operation prior to the insertion of the connecting plug P_1 .

The relay 188 being operated will close its contacts 99, closing the energizing circuit of the relay O , the holding circuit of 125 the relay R_7 and the plug circuit lamp 119 as follows:—from negative battery, the circuit conductor 120, the winding 121 of the relay O , circuit conductor 122, contacts 99 of the relay 188, circuit conductor 123, cir- 130

cuit conductor 170, the normally made contacts of the relay SO, circuit conductor 171, circuit conductor 12 and on Fig. 3 the conductor 12 leading to the now made contacts 5 117 of the relay R₇ by the conductor 124, and the holding winding 118 of the relay R₇, thence over the conductor 125, the signal lamp 119, the now made contacts 126 of the relay M, and then to the ground pole of 10 battery. Current will flow over this circuit energizing the relay O by its winding 121, and maintaining energized the relay R₇ by its holding winding 118.

The lamp 119 will not be lighted because 15 of the resistance of the winding 121 of the relay O being too high to allow sufficient current to flow in the circuit to light the lamp. This circuit being established and the relay O energized, its armatures will be 20 attracted and circuit changes will be made as will be described. Contacts 127 of the relay O will be closed thus providing a shunt of the contacts 99 of the relay 188, and thus providing a circuit for the holding 25 circuit just described independent of the contacts 99. The contacts 128 will now be closed, closing an energizing circuit for the supervisory lamp 129 as follows:—from the ground pole of battery, the contacts 30 128, the normally made contacts 130 of the relay 94, the calling lamp 129, and from thence to negative pole of battery. The lamp will be lighted until the response of 35 the called-for subscriber which will cause the relay 194 to be operated extinguishing the lamp as will be later described.

The energizing circuit for the relay U will now be severed by the normally made contacts 88 being broken, but the holding 40 circuit for the relay U which has been described will retain the relay U for the present in operation. The contacts 131 will also be closed to form a holding circuit for the trunk connections back to the line circuit and maintain them in operation independent of the contacts 31 of the calling subscriber's supervisory relay Q as follows:— 45 from the negative pole of battery, circuit conductor 89, the now closed contacts 131 of the relay O, circuit conductor 132, the circuit conductor 30, the now closed contacts 29 of the relay N, circuit conductor 133, the winding 134 of the relay N, circuit conductor 7 leading to conductor 7 of Fig. 55 1, the winding of the relay D₁, circuit conductor 28, the winding 135 of the relay R₆, the now made contacts 27 of the relay R₆, circuit conductor 26, the winding of the relay D, circuit conductor 136, the winding 60 137 of the relay R₁, the now made contacts 24 of the relay R₁, conductor 23, and from thence through the winding of the cut-off relay c to the positive ground pole of battery.

65 The relay R has been operated up to this

time maintaining the operator's telephone in circuit with the calling telephone line. The energizing circuit for the relay R has been as follows:—from the negative pole of battery, the now closed contacts 141 of the relay Q, the circuit conductor 142, the circuit conductor 143, the winding of the relay R, the circuit conductor 144, the normally made contacts 140 of the relay O, circuit conductor 145, the normally made contacts 75 39 of the common control relay P, the winding of the relay J, normally made contacts 146 of the relay W, and from thence to the positive or ground pole of battery. This circuit would be closed as long as the 80 operator was in conversational circuit with a telephone line, and the relay J would attract its armature closing an energizing circuit for a common listening lamp F which indicates to the operator whenever she is in 85 conversational circuit with a calling line, and this lamp circuit can be extended if desired to a supervisor's desk to inform the supervisor of the busy condition of the operator's circuit.

The relay R just described will now be broken by the severing of the contacts 140 when the relay O was energized restoring the relay R to normal. The relay R being restored to normal will open all of its make 90 contacts which have been closing circuits previously described. These circuits will now be opened including the circuits connecting the operator to the telephone line, and the original energizing circuits for the 100 ringing control relays T and S. These however are maintained in operation through the holding circuit, which holding circuit includes the conductor 147 leading to the ground pole of battery which is connected 105 by the contacts 148 to the conductor 55, thus replacing the connection to the ground pole of battery through the normally broken contacts 149, and the conductor 53 through the contacts of the key K₄ as was previously described. Thus the relays T and S are retained in operation regardless of the operation of the relay R after having been once operated, which operation must first take place when the relay R is energized. The other relays as the relay N operate 110 through make contacts of the relay R now also having established holding circuits independent of the contacts of the relay R in a manner which has been previously described. The ringing of the called subscriber will now continue until the subscriber responds by taking his receiver from the hook when the direct current from the source G will flow over the circuit of the 115 line and back through the trip relay V being superposed on the alternating current from the ringing generator, and will operate the relay V, short circuiting the winding 125 186 of the relay U deenergizing this relay caus- 130

ing it to be restored to normal, and thereby making its holding circuit at the contacts 91, and the relay will thereupon be maintained deenergized, unless reset by the operator, for 5 the remainder of the connection. When the relay U restored its contacts the relay 188 was deenergized, and the normally made contacts 150 and 151 were restored to normal condition, thus restoring the connection 10 of the talking strands 5 and 6 of the calling subscriber to connection with the outgoing talking strands 9 and 10 leading to the called-for subscriber's line, and the two parties will thereupon be in conversational 15 circuit. The called subscriber's supervisory relay 194 will now be energized over a circuit including the line conductors 113 and 114 of the called-for subscriber, the plug contacts 109 and 110, the closed contacts 20 of the relay R₁, circuit conductor 9 and 10, the now closed contacts 150 and 151 of the relay U, the now closed contacts 152 of the relay O, circuit conductor 153, circuit conductor 154, and the left hand winding of 25 the relay 94, also the circuit conductor 103 leading to the right hand winding of the relay 94; these windings being connected to the two poles of battery. This relay now being in circuit with the substation instrument 30 will attract its armatures extinguishing the called subscriber's supervisory lamp 129, and maintaining the winding 186 of the relay U open at now broken contacts 93.

When the relay O was operated the original energizing circuit which included the winding *a* of the relay N which lead to conductor 118 and thence to a common relay P to the negative pole of battery was interrupted at the contacts 144. A portion of 35 this circuit common to a plurality of incoming call circuits and which includes a conductor 118 and a relay P, was also at this time switched from connection to the incoming call circuit upon which a connection was 40 being established to the next succeeding incoming call circuit shown to the left of the Fig. 2, thus providing an original establishing circuit for this incoming call circuit to the next succeeding incoming call and which 45 circuit will include the winding of the relay P, the circuit conductor 154 and a like winding on a like relay to the winding *a* on the relay N of the call circuit whose operation I have above described. Also when the 50 relay O was energized the listening control circuit—the common part of which consists of the conductor 145, the contacts 39 of the relay P, the winding of the relay J, the normally made contacts 146 of the relay W, and 55 thence to ground was switched from the break contacts 140 to the make contacts 155, and thence to conductor 156 leading to the next succeeding incoming call circuit, and providing a common control circuit for the 60 operator's relay like the common control 65

circuit for the line operator's relay of the incoming call circuit whose operation I have just described. Thus the original establishing circuit of the incoming call circuits and the operator's control circuit for 70 the same is passed from one incoming call circuit to the other, unless a connection has been established on each of the incoming call circuits. A high resistance winding 157 is placed in the circuit of the conductor 158 leading to the negative pole of battery to the 75 make contacts 131 of the relay Q of each of the incoming call circuits, and is made so high that if two incoming calls were to be connected to the same incoming call circuit 80 that this relay would not supply sufficient current to maintain operated two sets of trunk connecting relays connected to the conductor 7, such as the relays R₆ and R₁, or any two of such relays belonging to different incoming trunk circuits, and therefore one of the two relays wrongly connected in multiple as may sometimes happen on simultaneous calls will be retired, the one being retired depending upon the adjustment of the relays. 85

The subscribers having completed their conversation will retire their substation instruments, or the calling subscriber may retire his substation instrument, and such an 90 act will cause the supervisory lamps of the two subscribers or such subscriber as retires his instrument to glow. Thus the called subscriber retiring, the battery supply supervisory relay 94 will be deenergized as is common in the ordinary type of 95 manual switch-board systems a supervisory lamp 129 will glow by the closing of the normally made contacts 130. The calling subscriber upon retiring will cause the deenergization of the calling supervisory relay Q which will cause the lighting of the 100 calling supervisory lamp 160, and the disconnect lamp shown in connection with the plug circuit of Fig. 3 at 119 by the operation of circuits as follows:—The left hand armature of the relay Q being restored to normal, the normally closed contacts 161 will be closed operating the relay 97, and 105 starting in operation the slow operating relay SO which may be as indicated in the drawing, a thermal relay, or a relay having any equivalent mechanical means of retarding its action, over a circuit as follows:—from the negative pole of battery, 110 the conductor 81, the normally closed contacts 162 of the key K₅, circuit conductor 163, right-hand winding of the relay 97, and winding of the slow operating relay 115 SO in parallel, the circuit conductor leading to the normally closed contacts 161 of the relay W, the circuit conductor 132, the now closed contacts 131 of the relay O, and from thence to the negative pole of battery. This causes the operation of the re- 120 125 130

lay 97 at once, and after a length of time which may be predetermined by the construction of the relay SO and by its adjustment, relay SO will also be operated. Such an interval may be 5 or 10 seconds.

The relay Q being released will operate the lamp 119 shown in Fig. 3, over a circuit which has been previously described as including this lamp, and which has been described as including a high resistance winding 121 of the relay O. One terminal of this winding being described as being connected to the negative pole of battery, the other leading by make contacts 127 of the relay O through normally made contacts *a* of the relay SO, and from thence by means of conductors 12, etc., to lamp. The winding 121 has maintained the lamp in an unlighted condition due to the high resistance of this winding. The relay Q being released however, will furnish battery to the lamp over a low resistance winding 164 of the relay O by means of circuit conductor 165, normally closed contacts 166 of the key K₅, circuit conductor 167, the now closed normal contacts 168 of relay Q, and from thence to negative pole of battery. The lamp 119 of the plug circuit will be lighted through this low resistance winding 164 giving the disconnect signal to the operator. The relay 97 being operated will attract its armatures, switching a circuit to be described. The left-hand armature being attracted closes contacts 172 forming a locking circuit for the relay 97 independent of the contacts 161 of the relay Q. The contacts 172 independently maintain energized the relay 97 over a circuit traced as follows:—from the negative pole of battery, conductor 81, the normally closed contacts 162 of the key K₅, circuit conductor 163, the left-hand winding of the relay 97, contacts 172 of the relay 97, circuit conductor 173, circuit conductor 33, the now closed contacts 29 of the relay N, circuit conductor 30, circuit conductor 132, the now closed contacts 131 of the relay O, and from thence to negative pole of battery.

The first pair of contacts to the right of the magnet of the relay 97 is now closed conditioning a circuit for the lamp 160, but this circuit will remain for the present open at the contacts 174. The contacts 96 will be broken breaking the circuit of the winding 186 of the ringing relay U for the purpose of restoring the ringing relay to normal in case the called-for subscriber should not have responded previously, thus restoring the relay U in the manner which has been previously described.

If the subscriber making a recall energizes the relay Q, the relay 97 being maintained operated, the lamp 160 will now be flashed in a characteristic manner by the ac-

tion of the interrupter 178, over a circuit as follows:—from the negative pole of battery, the interrupter 178, the circuit conductor 177, the now closed contacts 280 of the relay 97, the now closed contacts 174 of the relay Q, the lamp 160, and from thence to the negative pole of battery. The operator observing the flashing lamp will depress the key K₅, thereupon switching the circuits as follows:—the circuit of the relay 97 will be opened by the contacts 182, restoring the relay. The contacts 180 of the relay 179 constantly operated by the interrupter 178, thereupon produces a source of interrupter negative battery current, and this source of interrupted battery current is substituted for the source of steady negative battery current previously supplied over the conductor 167 and the normally made contacts 166 of the key K₅ through the winding 164 of the relay O, and the winding 118 of the relay R₇ to the lamp 119, by the opening of the contacts 166 of the key K₅, and the closing of contacts 181 of this key, connecting the interrupter negative battery source to the conductor 165 leading to the lamp 119. The lamp 119 will thereupon be rapidly flashed in a characteristic manner apprising the operator as to which plug circuit was at the time connected to the incoming call circuit in which the key K₅ resides. The contacts 166 and 181 are so adjusted that the contacts 166 will not break until the contacts 181 are made, and therefore there will be no breaking of the circuit which includes the winding 164 and 118 of the relay O and R₇, and these relays therefore will be maintained in their operated condition being capable of being maintained by such a source of current as is supplied by the relay 178. This is accomplished by adjustment of the relays, or by making them slow releasing in the well-known manner; or by having the break of the interrupter current of very short duration.

The operator pressing the key K₅ also breaks the circuit of the winding 186 of the relay U and at the normally made contacts 88, restoring the ringing relay to normal in case the operator presses this key prior to the response of the called-for subscriber. The closing of the contacts 80 by the key K₅ lights one of the indicating lamps 70, 71, 72 and 73 as is determined by the condition of the operation of the relays T and S to indicate to the operator the kind of ringing current which has been previously set in the incoming call circuit. The contacts 183 being closed operate the operator's listening relay R so that the operator's telephone is again connected to the talking strands of the incoming call circuit, also in circuit with the contacts 183 and the winding of the operator's relay R. The winding 130

- 190 for the relay O is placed so that the relay O will be maintained in operation all of the time the operator's key K_5 is depressed, and the operator will then converse 5 with the recalling subscriber and upon being advised what connection is desired, if any, can carry out the wishes of the subscriber either taking down the existing connection by means of the plug P_1 of the plug 10 circuit, which is identified by the operator by means of the flashing lamp 119, or can also establish another connection using this or any other talking circuit not in use; or can break down the existing ringing condition 15 set up by the relays T and S by means of the key K_4 in the manner previously described, and set up a new ringing condition by means of the keys K_2 or K_3 . After so doing the operator will restore the key K_5 , 20 after which the circuits will be restored to their normal condition for the connection period. Should the operator get a disconnect signal by the steady lighting of the lamp 119, the taking down of the connection 25 will release relays N and R₁ of the plug circuit of Fig. 3, and the relay O of Fig. 2. The relay O of Fig. 2, being released will release all of the apparatus of the circuits of Fig. 2 and Fig. 1 involved in the connection, thus restoring all of the circuits to 30 normal.
- At the time an incoming call is connected to an incoming call circuit, a circuit is completed for a signal lamp 200 shown in Fig. 35 2, including a source of battery, the contacts 201 of the relay N, the signal lamp 200, the circuit conductor 202, the normally made contacts 203 of the relay O, and from thence to the ground pole of battery. Therefore, the lamp 200 will be lighted and will 40 serve as an indicating lamp to the operator as to which incoming call circuit has been taken for use by the call distributing trunks. The operator may complete a connection 45 without having this knowledge, but in the system of my invention, I provide the lamp 200, so that the operator may handle the call as intelligently as possible; and in such a way as to give the subscriber the benefit of 50 the fullest supervision of his call, as well as to relieve the operator of any doubt which might be in her mind and thereby cause a hesitation as to an operative act, and thereby by a loss of time.
- 55 The relay W which is common to an operator's position will be operated each time that the key K_5 is depressed, since the winding of the relay W is placed in the circuits of the indicating lamps 70, 71, 72 and 73 60 one of which is lighted each time the key K_5 is depressed by current flowing through the lamp; and also through the winding of the relay W. The relay W attracts its armatures breaking the normally made contacts 65 146, and thereby removing the ground con-
- nection from the conductor 145, which ground is required to be connected to this conductor in order that the operator's telephone set may be automatically connected to any call circuit by means of the relay 70 R. Thus when the operator is attending a call circuit and has the key K_5 depressed, the depressal of such a key in one of the call circuits bars her telephone set from being automatically connected to another incoming call circuit. As the circuits are arranged however, at the time the operator is so attending an incoming call circuit using a key K_5 as when making a recall, another incoming call circuit may be taken for use 80 by an incoming call which the operator can attend as soon as she has disposed of the recall and has therefore restored her key K_5 , as she will do after attending a recall.
- I claim—
1. In a telephone system, the combination of interconnecting trunk circuits, relays to interconnect said trunk circuits, relays to prevent one of said trunk circuits being connected with more than one of said interconnecting trunks at a time to incoming call circuits, relay means to interconnect one of said trunks to said incoming call circuit, and delayed disconnect means to disassociate said incoming call circuit and said trunk 95 circuit.
2. In a telephone system, the combination of a plurality of telephone lines, a plurality of operators' connecting circuits therefor, common key means for setting up a predetermined ringing condition in any of said circuits, common signal devices for indicating the ringing condition set up in any connecting circuit, and an operator's listening key for each of said connecting circuits, said 100 listening keys controlling said signal devices.
3. In a telephone system, the combination of a plurality of connecting circuits therefor, a plurality of ringing relays for each of said connecting circuits, a common set of keys for controlling said ringing relays, a common signal circuit controlled by said ringing relays, and a listening key individual to each of the connecting circuits, said listening key controlling said signal circuit.
4. In a telephone system, the combination of a plurality of incoming call circuits therefor, a plurality of ringing relays for each of said incoming call circuits, an operator's 120 circuit, listening keys in the connecting circuits for connecting said operator's circuit to the talking conductors of the incoming call circuits, a key common to the incoming call circuits for said ringing relays and common indicating means for said incoming call circuits, said indicating means being under the control of said ringing relays, said common key and said listening key of an incoming call circuit.

5. In a telephone system, the combination of a plurality of operators' connecting circuits therefor, a plurality of ringing relays for each of said connecting circuits, a listening key for each of said connecting circuits, a common key for said ringing relays, and a common signal circuit under the joint control of said ringing relays, said common and said listening key.
- 10 6. In a telephone system, the combination of a plurality of telephone connecting circuits, a common key means for setting up a predetermined ringing condition in any of said connecting circuits, common signal devices for indicating the ringing condition set up in any connecting circuit, individual key means controlling said common signal devices, an operator's circuit, and talking conductors for said telephone connecting circuits, said individual key means being adapted to connect said operator's circuit to the talking conductors of any connecting circuit to operate one of said indicating signal devices.
- 15 7. In a telephone system, the combination of an operator's link circuit, a plurality of incoming trunks, a plurality of telephone lines, substations for said lines, means responsive to the actuation of substation apparatus to connect the associated line with one of said trunks, a means responsive to said connection to connect said trunk to said link circuit, a substation controlled relay in said link circuit, a flashing recall relay for said link circuit under the control of said substation controlled relay, said substation controlled relay operating said flashing recall relay upon the restoring of said substation apparatus to normal, a signal lamp for said link circuit controlled by said flashing recall relay and said substation controlled relay, circuit connections to cause said lamp to show a disconnect signal upon the retiring of said substation apparatus, a locking circuit for said link circuit whereby said link circuit is locked with a connected incoming trunk circuit, substation controlled means to disassociate said link circuit from said incoming trunk circuit by the release of said locking circuit, automatic timing means to operate upon the retiring of said substation apparatus, and circuit connections to cause said timing means to release said locking circuit after a predetermined interval determined by the ultimate operation of said timing means.
- 20 8. In a telephone system, the combination of a plurality of telephone lines, substations for said lines, operator's link circuit, automatic means to connect a calling one of said lines to said link circuit, automatic means to release said link circuit from said line, a relay in said link circuit under the control of said substation apparatus, said relay controlling said automatic disconnect

means, time limit apparatus under the control of said relay to delay the operation of said disconnect means, a disconnect signal and a recall relay for said link circuit, said recall relay controlling said disconnect signal when said substation apparatus is operated to make a recall and cause said signal to flash in a characteristic manner, said time limit apparatus controlling said recall relay.

75 9. In an operator's incoming call circuit, the combination of answering terminals therefor, ringing generator selecting relays connected to said answering terminals, said subscriber's controlling relay controlling said generator, selecting relays, a plurality of connecting plugs, connecting means for said connecting plugs to connect a manually selected one of said plugs with said incoming call circuit, a plurality of ringing generators adapted to be selected by said generator selecting relays, a ringing relay to extend the connection of said selected generator to a manually selected plug circuit, said ringing relay being under the control of said plug circuit connecting means.

90 10. In a telephone system, the combination of an operator's incoming call circuit of answering terminals therefor, a subscriber controlled relay connected to two of said answering terminals whereby said subscriber controlled relay is connected to the talking strands of a telephone line, ringing generator selecting relays, said subscriber controlled relay controlling said generator selecting relays, a plurality of connecting plugs, connecting means for said connecting plugs to connect a manually selected one of said plugs with said incoming call circuit, 105 a plurality of ringing generators adapted to be selected by said generator selecting relays, and a ringing relay to extend the connection of said selected generator to a manually selected plug circuit, said ringing relay being under the control of said plug circuit connecting means.

110 11. In a telephone system, the combination of an operator's incoming call circuit of answering terminals therefor, a subscriber controlled relay connected to two of said answering terminals whereby said subscriber controlled relay is connected to the talking strands of a telephone line, ringing generator selecting relays, said subscriber controlled relay controlling said generator selecting relays, a plurality of connecting plugs, connecting means for said connecting plugs to connect a manually selected one of said plugs with said incoming call circuit, 115 a plurality of ringing generators adapted to be selected by said generator selecting relays, and a ringing relay to extend the connection of said selected generator to a manually selected plug circuit, said ring-

ing relay being under the control of said plug circuit connecting means and called substation, said ringing relay being under the control of said called and calling substation apparatus.

12. In a telephone system, the combination of an operator's incoming call circuit of answering terminals therefor, a subscriber controlled relay connected to two of said answering terminals whereby said subscriber controlled relay is connected to the talking strands of a telephone line, ringing generator selecting relays, said subscriber controlled relay controlling said generator selecting relays, a plurality of connecting plugs, connecting means for said connecting plugs to connect a manually selected one of said plugs with said incoming call circuit, a plurality of ringing generators adapted to be selected by said generator selecting relay, a ringing relay to extend the connection of said selected generator to a manually selected plug circuit, said ringing relay being under the control of said plug circuit connecting means and called substation, an operator's listening key and a listening relay controlled thereby, said ringing relay and said generator selecting relays being under the control of said listening key.
13. In a telephone system, the combination of an operator's incoming call circuit of answering terminals therefor, a subscriber controlled relay connected to two of said answering terminals whereby said subscriber controlled relay is connected to the talking strands of a telephone line, ringing generator selecting relays, said subscriber controlled relay controlling said generator selecting relays, a plurality of connecting plugs, connecting means for said connecting plugs to connect a manually selected one of said plugs with said incoming call circuit, a plurality of ringing generators adapted to be selected by said generator selecting relay, a ringing relay to extend the connection of said selected generator to a manually selected plug circuit, said ringing relay being under the control of said plug circuit connecting means and called substation, an operator's listening key and a listening relay controlled thereby, said ringing relay and said generator selecting relays being under the control of said listening key and said operator's listening relay.
14. In a telephone system, the combination of a plurality of telephone lines, extended by their limbs from substations to an exchange, a plurality of operators' link circuits therefor, automatic listening means to connect the subscriber's telephone set to the talking strands of the link circuit, an operator's listening key in each of said link circuits, a supervisory recall lamp for each of said link circuits, said listening key controlling said recall lamp, and means under

the control of said key to prevent the operation of the said automatic listening means of another of said link circuits.

15. In a telephone system, the combination of a plurality of telephone lines, a plurality of link circuits for interconnecting a calling and called one of the said lines, switching means to connect a calling one of the said lines to the said link circuit, a group of switches adapted to make connection with called lines, a ringing key for each of the said link circuits, means to interconnect any of the said switches with any of the said link circuits, said means being under the joint control of the said ringing key of a link circuit and an operated one of the said interconnecting means.

16. In a telephone system, the combination of a link circuit, calling terminals therefor, called terminals for said link circuit normally disassociated therefrom, a ringing key adapted when operated to apply ringing current in the direction of the called terminals, and connection extending means under the control of said ringing key to automatically interconnect the said link circuit and the said called terminals.

17. In a telephone system, the combination of a plurality of telephone lines, an interconnecting trunk for said line, a plurality of connecting marginal relays for said trunk, multiple energizing circuits for said connecting relays, each of said relays being individual to one of said lines to interconnect said line with said trunk, the said individual relay for the said line being in one of the said multiple circuits lower in resistance than the other multiple circuits containing other connecting relays, and a relay for said trunk to disable said connecting relay when said trunk is taken for use by the connecting relay of a prior connecting line.

18. In a telephone trunking system, the combination of a plurality of telephone lines extending by their limbs from substations to an exchange, a plurality of relays for each of said lines, a plurality of trunks for each of the relays of a line, a controlling line relay for said relays, a cut-off relay for said line adapted to be controlled by said relays, busy relays individual to said trunks, each of said busy relays adapted to control the connection of a calling line to its trunk if said trunk is not busy, and a circuit including a winding of said busy relay, a winding of a trunk connecting relay and said cut-off relay whereby these relays are operated serially on an established connection between a line and a connected trunk.

19. In a telephone system, the combination of a calling line, a plurality of trunks for said line, a plurality of marginal relays common to said line, a plurality of energizing circuits, one for each of the said re-

lays, the said circuits being all connected in multiple, each being individual to one of said trunks to interconnect said line with a selected one of said trunks, and circuit connections for each of the said trunk lines connected in the multiple energizing circuit of the associated line relay to make the multiple energizing circuit of such a relay of lower resistance than the other multiple circuits, a relay for each of said trunks to disable said connecting relay when said trunk line is taken for use by the connecting relay by a prior connected calling line.

20. In a telephone system, the combination of a plurality of telephone lines, a trunk line for said lines, a plurality of relays common to said trunk line and individual each to an associated one of said lines for interconnecting said trunk line with one of said lines, and a relay having its winding in serial circuit with a winding of a connecting relay of a connected line to prevent the subsequent connection by another of said relays of the trunk line and the line of said interconnecting relay.

21. In a telephone system, the combination of a plurality of telephone lines, a trunk line for said lines, a plurality of relays common to said trunk line and individual each to an associated one of said lines for interconnecting said trunk line with one of said lines, and a relay having its winding in serial circuit with a winding of a connecting relay of a connected line to prevent the subsequent connection by another of said relays of the trunk line and the line of said interconnecting relay, said serial connection comprising locking contacts of said connecting relay.

40. 22. In a telephone system, the combination of a plurality of telephone lines, a trunk line for said lines, a plurality of relays common to said trunk line and individual each to an associated one of said lines for interconnecting said trunk with one of said lines, a relay having its winding in serial circuit with a winding of a connecting relay of a connected line to prevent the subsequent connection by another of said relays of the trunk line and the line of said interconnecting relay, said serial connection comprising locking contacts of said connecting relay, a cut-off relay for each of said lines, locking contacts for each of said connecting relays, said cut-off relay and said locking contacts being included in the said serial circuit of an established connection.

23. In a telephone trunking system, the combination of a calling line, a primary trunk for said line, a secondary trunk for said primary trunk, a tertiary trunk for said secondary trunk, relay means to connect said primary trunk with said secondary trunk, relay means to connect said secondary trunk with said tertiary trunk, a cut-off re-

lay for said line, a relay to connect said tertiary trunk with an operator's incoming calling circuit, and controlling contacts in said operator's incoming call circuit included in a circuit comprising windings of all of said connecting relays and said line cut-off relay.

24. In a telephone system, the combination of a calling line, trunks of two dimensions for extending a connection over said line and an operator's calling circuit, a relay to interconnect non-busy trunks of the two dimensions, a cut-off relay for the line, and a locking circuit for said first named relay including contacts thereof, said locking circuit including contacts thereof, a winding thereof, and a winding of said cut-off relay.

25. In a telephone trunking system, the combination of a telephone line, a plurality of marginal relays associated with said line, a plurality of energizing circuits, one for each of the said relays, the said circuits being all connected in multiple, each adapted to connect said line with an associated trunk circuit, a plurality of marginal relays for said trunk circuit, a plurality of multiply connected energizing circuits for each of the said relays, each adapted to connect said trunk circuit with an operator's call circuit, and circuit connections associated with said lines and with said call circuits, whereby one of said first named group of relays and one of said second named group of relays have their energizing circuits made lower in resistance to an incoming call impulse, whereby the said relays are operated and the other multiply connected relays remain quiescent, controlling contacts in said operator's call circuit included in serial circuit with a winding, and a contact of each of said connecting relays connecting said line in said incoming call circuit.

26. In a telephone system, the combination of a telephone line, a plurality of relays for said line, said relays being adapted to connect the said line with the first idle one of said trunk circuits, a busy relay individual to each of said trunks and responsive to the idle condition of its trunk circuits to cause said line to be connected by one of its associated connecting relays with said trunk line, and a locking circuit including a winding of said busy relay and said marginal connecting relay.

27. In a telephone system, the combination of a calling telephone line, a plurality of marginal connecting relays for said line, a plurality of trunk lines for said line, each of said relays being individual to one of said trunks, multiply connected energizing circuits for said marginal relays, each of said circuits being lower in resistance than the remainder of the said circuits under a given operative condition of the said telephone

lines, preselecting means to preselect a trunk line to be interconnected with the said line, the said preselecting means controlling the low resistance condition of an associated one of the said energizing circuits.

28. In a telephone system, the combination of a group of incoming call circuits, a group of manually operated switches therefore, electromagnetic means for interchangeably associating any manually selected switch with any incoming call circuit as is in a partially connected condition; a disconnect signal for said manually operated switches, and means to cause said signal to 15 flash in a characteristic manner.

29. In a telephone system, the combination of a group of telephone lines terminating at a central office, incoming call circuits for said telephone lines, manually operated 20 switches for extending a connection from an incoming call circuit to a called telephone line, interconnecting means for associating an incoming call circuit with the said manually operated switches, and apparatus under 25 the control of each of said manually operated switches for selecting a particular interconnecting means to connect a calling telephone line with a called telephone line by means of said manual switch.

30. In a telephone system, the combination of a group of telephone lines terminating at a central office, incoming call circuits for said telephone lines, manually operated switches for extending a connection from an 35 incoming call circuit to a called telephone line, interconnecting means for associating an incoming call circuit with the said manually operated switches, and apparatus under the control of each of said manually operated 40 switches for selecting a particular interconnecting means to connect an incoming call circuit with a called telephone line by means of said manual switch.

31. In a telephone system, the combination 45 of a plurality of telephone lines terminating at a central office, a group of incoming call circuits for said telephone lines, call distributing trunks to connect a calling telephone line with an incoming call circuit 50 of the group, a group of outgoing call circuits associated with said incoming call circuit group, automatic interconnecting means for interconnecting any manually selected outgoing call circuit with an incoming call 55 circuit to which is connected a calling line, and a manual switch for said outgoing call circuit adapted to connect said outgoing call circuit to a desired called line, said interconnecting means being under the control 60 of said manual switch and the calling telephone line.

32. In a telephone system, the combination 65 of a plurality of telephone lines terminating at a central office, a group of incoming call circuits for said telephone

lines, call distributing trunks to connect a calling telephone line with an incoming call circuit of the group, a group of outgoing call circuits associated with said incoming call circuit group, automatic interconnecting means for interconnecting any manually selected outgoing call circuit with an incoming call circuit to which is connected a calling line, and a manual switch for said outgoing call circuit adapted to connect 70 said outgoing call circuit to a desired called line, said interconnecting means being under the control of said manual switch.

33. In a telephone system, the combination of a group of incoming call circuits, a 80 group of manually operated switches associated therewith, and electromagnetic means for interchangeably associating any manually selected manual switch with such incoming call circuit as is in a partially connected 85 condition.

34. In a telephone system, the combination of a group of incoming call circuits, related manually operated switches, and electromagnetic means for interchangeably associating any of the manual switches with any of the incoming call circuits, said electromagnetic means being under the control 90 of said manually operated switches.

35. In a telephone system, the combination of a group of incoming call circuits, a group of manually operated switches associated therewith, means for storing incoming calls in said call circuits, means to prevent more than one uncompleted call to be 95 stored in the said group of call circuits at one time, electromagnetic means for interchangeably associating any of the manual switches with the said incoming call circuit in which a call is stored, and a manually 100 selected one of said switches for operating the electromagnetic means to associate the said electromagnetic switch with the incoming calling circuit in which the call is stored.

36. In a telephone system, the combination of a plurality of subscribers' stations, telephone lines for said stations, connecting contacts for said lines, a plurality of cord circuits, said cord circuits being provided with connecting plugs for insertion within 110 said circuits, operators' incoming call circuits, selective switching mechanism in circuit relation with said incoming call circuits for uniting calling telephone lines with calling line connecting trunk circuits, and means 115 including said selective mechanism operated by the act of insertion of a connecting plug into a line jack to cause the cord circuit with which is associated the said connecting plug to be connected to the calling line connected 120 trunk circuit.

37. In a telephone system, the combination of a plurality of telephone lines, one of said lines being a calling line, a trunk circuit common to a plurality of said lines to 130

connect a calling one of said lines with a non-busy operator's incoming call circuit, operator's cord circuits, and means operated by the insertion of a plug of said cord circuit into the jack of a called-for line to cause said cord circuit to be connected with said calling line.

38. In a telephone system, the combination of a plurality of telephone lines terminating at a central office, a group of incoming call circuits therefor, a group of manually operated switches associated with said group of call circuits, said manually operated switches being adapted to connect with said telephone lines, and electromagnetic means under the control of said manually operated switches for interchangeably associating any of said manually operated switches with any one of said incoming call circuits.

39. In a telephone system, the combination of an operator's incoming call circuit of normally disassociated calling and called terminals therefor, substation controlled means to connect a calling line to the calling terminals of said operator's call circuit, operator controlled means to connect a manually operated switch plug to said called terminals, and an automatic line finding switch responsive to an operated operator controlled means to interconnect the said manually operated switch plug and the said calling line.

40. In a telephone system, an operator's call circuit, the combination of normally disassociated calling and answering terminals therefor, subscriber controlled connecting means for said answering terminals, operator controlled connecting means for said calling terminals, said operator controlling means consisting of a plug and jack switch, and an automatic switch to extend a connection from a subscriber's line to a called line, said automatic switch being actuated after the actuation of the said plug and jack switch.

41. In a telephone system, the combination of a plurality of telephone lines, substations on said lines, a plurality of plug circuits normally disassociated from said lines, a plurality of operators' call circuits normally disassociated from said lines and said plug circuits, substation controlled means to connect a calling one of said lines with an idle one of said call circuits, means to connect any one of said plug circuits to any one of said call circuits, and a manually operated switch operated in making connection with a called telephone line, to operate

said connecting means to automatically connect a manually selected one of said plug circuits to one of said call circuits, a selective portion of said connecting means also being under the control of the substation apparatus of the calling line.

42. In a telephone system, the combination of a plurality of telephone lines, substations on said lines, a plurality of plug circuits normally disassociated from said lines, a plurality of incoming call circuits, 70 substation controlled means to connect a calling one of said lines with an idle one of said call circuits, means individual to each plug circuit to connect the said plug circuits to any one of said call circuits, and a manually operated switch operated in making connection with a call telephone line.

43. In a telephone system, the combination of a plurality of telephone lines extending by their limbs from substations to an 80 exchange, terminal jacks for said lines, a plurality of plug circuits, manually operated terminals therefor and adapted to make connection with said jacks, and automatic connecting means associated with said plug 85 circuits to operate when said connection is made to connect a manually selected one of said plug circuits with a calling telephone line.

44. In a telephone system, the combination of calling telephone lines, operators' call circuits therefor, means to connect a calling one of said lines to an idle one of said call circuits, subsequent operating means controlled by the said connection to 95 cause the next calling line to be connected with a second operator's call circuit, normally disconnected calling terminals for said call circuits, a plurality of control switches adapted to connect one with each 100 of said calling lines, and controlling means in said call circuits to determine which of said lines is to be connected to a called telephone line by each of said switches.

45. In a telephone system, the method of 105 interconnecting telephone lines by causing the incoming call from one telephone line to be connected to an idle telephone operator's telephone set whereby a call is received, and the subsequent completion of the connection 110 to a called-for subscriber's line by making connection with the called-for line by means of any one of a group of manually selected cord circuits.

In witness whereof I hereunto subscribe 115 my name this 29th day of March, A. D. 1917.

FRANK M. SLOUGH.
